UNITED STATES PATENT OFFICE.

HAROLD S. OSBORNE, OF NEW YORK, N. Y., ASSIGNOR TO AMERICAN TELEPHONE AND TELEGRAPH COMPANY, A CORPORATION OF NEW YORK.

COMPOSITE PHANTOM CIRCUITS.

1,374,221.

Specification of Letters Patent.

Patented Apr. 12, 1921.

Application filed February 12, 1919. Serial No. 276,487.

To all whom it may concern:

Be it known that I, HAROLD S. OSBORNE, residing at New York, in the county of New York and State of New York, have invented 5 certain Improvements in Composite Phantom Circuits, of which the following is a specification.

This invention relates to signaling systems, and particularly those in which telephone and telegraphic communication are 10 had over the same conductors.

The invention is related to that disclosed in copending application Serial No. 266,326, filed December 11, 1918, in which provision 15 is made for using complete metallic telegraph circuits co-incident for the most part with the telephone circuits, and employing small telegraphic currents of the same order of magnitude as the telephone currents. One 20 object of the present invention is to provide for both side circuit and phantom circuit transmission of the telegraph signals in one way channels. Another object is to provide a system of high pass and low pass filters 25 for separating the telephone and telegraph currents in such a system.

The invention will be more fully described in connection with the accompanying drawing in which the single figure illustrates dia- 30 grammatically a system embodying this invention.

Two metallic circuits 1 and 2 are here 35 shown as constituting the side circuits for telephone transmission, and these are connected to produce a phantom circuit for tele- 40 phone communication in the usual way by leads tapped off at the central points of the transformers 3. These telephone channels may be either one way or two way circuits. 45 If they are one way circuits they will, ordi- narily though not necessarily, be combined with other one way circuits to form what is known as a four wire circuit, or the equivalent, so that communication in either direc- 50 tion may be had.

Telegraphic sending apparatus may be located at one end of the transmission line, and telegraphic receiving apparatus at the other, as shown in the drawing, the intention 55 being in this case to use the circuits for one way transmission only for telegraphic purposes. A sending set 4 is bridged across each of the circuits 1 and 2, and comprises a single source of current 5 connected to a pole changer 6. In the form shown, the pole

changer consists of a pair of arms moving in unison and connected to the opposite poles of the current source. These are ar- 60 ranged to vibrate between contacts connect- ed to the conductors which bridge the cir- 65 cuits 1 and 2, each conductor running to a contact associated with each arm and lying on opposite sides of the respective arms so that the movement of the arms from one side to the other will reverse the current in 70 a well-known manner. It will be under- 75 stood, that any known form of pole changer may be used. It may be desirable in some cases however, that the pole changer be ar- 80 ranged as shown to have make-before-break 70 contact so that the circuit is never actually opened; and to prevent the current source from being short circuited when the pole changer is at rest, it may then be biased to one position by a spring, as indicated in the 75 drawing, and operated in the other direction by a magnet under the control of the tele- 85 graph key. Obviously however, other biasing means such as an ordinary polarized relay may be employed, if desired. The re- 90 sistance customarily employed in series with the sending battery is divided into equal sections which are located on opposite sides of the source, as shown at 7-7', so that the impedance between either side of the line 85 and the central point 8 of the battery 5 will be the same.

From the central points 8 of the batteries associated with the circuits 1 and 2, are leads 9 to which a third sending set 10 is connected. 90 This set is similar in all respects to sending sets 4 above described.

The telegraphic receiving apparatus is here represented by a simple magnet 16, it being understood that any suitable receiving 95 instrument may be used, provided the wind- 100 ings thereof are so disposed that they afford mid or neutral points 17 for those re- 105lays which are connected immediately across the respective side circuits 1 and 2. The phantom receiving relay is connected between the neutral points of the side circuit relays as indicated on the drawing.

For separating the telephone and tele- 105 graph currents at either end of the line is an arrangement of properly tuned filter cir- 110 110 cuits of a general character now well-known in the art. For the arrangement of circuits here shown, the high pass filter for the side telephone circuits may consist of a capacity

11 inserted in each side of the circuit, coöperating with an inductance 12 shunted across the circuit, though, as is well understood, the inductance of the transformer windings 5 3 may be relied upon, and the special inductances 12 omitted in certain instances. The phantom telephone circuit is here provided with its own high pass filter, shown as capacity 11', in series with each phantom 10 lead, and inductance 12' bridged across the phantom leads. In like manner each of the side circuits of the telegraph branches is provided with its own low pass filter, consisting of inductances 13 in series with the 15 line, and capacities 14 in shunt thereto, and the phantom telegraph branch has its individual low pass filter composed of similarly arranged inductances and capacities 13' and 14', located in the leads running to 20 the central points 8 in the side circuit apparatus.

At the receiving end of the system, low 25 pass filters 15 and 15' are arranged in the side and phantom telegraph circuits and high pass filters 18 and 18' in the side and phantom telephone circuits in the same manner as just described for the transmitting end. These filters may be of the same construction as the corresponding filters at the 30 sending end, though it is not usually necessary that they be composed of as many sections. At the sending end, the filters must serve not only to prevent the shunting of the telephone currents, but must prevent the 35 higher harmonics, resulting from the operation of the sending instruments, from reaching the telephone instruments. At the receiving end, this latter function is not required of the filters, and in many instances 40 one section will be sufficient.

It is to be understood that the invention is not limited to the details herein described, since it is obvious that many modifications 45 may be made within the scope of the appended claims, without departing from the spirit of the invention.

What is claimed is:

1. In a signaling system, the combination 50 of two pairs of line conductors, telephone apparatus connected to said conductors to provide two side circuits and one phantom

circuit, telegraph apparatus bridged across each pair of conductors forming one of said side circuits, said apparatus including a sending set whose elements are arranged to 55 provide a mid or neutral point with respect to the side circuit conductors, and other telegraph apparatus connected between said neutral points.

2. In a signaling system, the combination 60 of two pairs of line conductors, telephone apparatus connected to said line conductors to provide two side circuits and one phantom circuit, telegraph sending apparatus connected across each side circuit and including a single source of current and a pole changer for reversing its relation to the conductors leading to said side circuit, a mid or neutral point in each of said sources of current and other telegraph sending apparatus connected between said mid or neutral points. 65

3. In a signaling system, two pairs of line conductors, telephone apparatus connected to said pairs of line conductors to form two 70 side circuits and one phantom circuit, telegraph apparatus connected for one-way transmission to said pairs of conductors to form two side circuits and one phantom circuit, high pass filters respectively individual 75 to said side and phantom circuits connected in the branches leading to the telephone apparatus, low pass filters respectively individual to the side and phantom telegraph circuits connected in the branches leading 80 to the transmitting and receiving ends of said circuits, the filters in the receiving end of said telegraph circuit having constants designed for the separation of the relatively weak received currents, and the filters at 85 the transmitting end of said telegraph circuits having constants designed to prevent the relatively strong transmitted impulses from entering the telephone branches of the circuit and to suppress the higher harmonics 90 of the transmitted impulses sufficiently to prevent interference with the telephone transmission. 95

In testimony whereof I have signed my name to this specification this tenth day of February, 1919.

HAROLD S. OSBORNE.
